UNITED STATES PATENT OFFICE

REGINALD PAULSEN, OF OSLO, NORWAY

TANK SHIP

Application filed January 20, 1928, Serial No. 248,187, and in Norway February 3, 1927.

This invention concerns improvements in tank ships of the two-deck type and is characterized by the vessel having an expansion trunk or upward extension of the main tank-space projecting from the second deck through the main deck to an appropriate level above the latter. In tank-ships of the two deck type as known hitherto the said trunk extended up to the main deck only.

The arrangement according to the present invention results in various advantages among which may be mentioned the greater volumetric capacity and depth which are obtained without any alteration of the dimensions of the vessel. Furthermore the extension of the expansion trunk through the main deck enhances the rigidity of the vessel, increasing its strength both longitudinally and transversely. A further advantage is that the vessel can be charged up to the loading line without regard being paid to whether heavy oil, petroleum or light benzine is being loaded. On account of the increased depth and cubic capacity the costs of construction per ton dead weight are less than those of tank-ships hitherto known of the same tonnage. Finally it may be mentioned that the stability alters but little when different oils are transported, this leading in turn to a reduction of the stress in the material and also of the leakage.

One embodiment of the invention is illustrated by way of example in the accompanying drawing which is a diagrammatic cross section of the vessel.

Referring to the drawing the reference numeral 1 indicates the shell of the vessel, 2 the main deck, 3 the second deck, 4 the amidship partition and 5 the usual summer tanks. The expansion trunk 6 extends up to its top 7 and communicates with the main tank spaces 8, 9. The walls of the expansion trunk extending longitudinally of the vessel are indicated by the reference numeral 10.

The extra rigidity imparted by the arrange-

ment of the trunk according to the invention enables the dimensions of the vessel and the dimensions of the material employed in its construction to be reduced, other economic advantages, or improvements of existing advantages, being thereby attained.

It is also to be noted that the working expenses for redemption and assurances are reduced on account of the decreased costs of construction. The fuel consumption is less because the driving machinery is of lower power than was hitherto the case with known tank-ships of the same carrying capacity by reason of the material reduction of the displacement of the vessel per ton dead-weight. In conclusion those fees and dues which are calculated upon the registered tonnage, such as for example harbour dues, are reduced because the registered tonnage per dead-weight ton is less as a consequence of the smaller main dimensions.

The details of the vessel and of its construction may be selected as desired and may be modified to conform with particular conditions which may be encountered in any individual case.

Claims:

1. A tank ship comprising a shell, a main deck, a second deck, an expansion trunk extending from the second deck up through and to a point above the main deck and having walls extending longitudinally of the vessel and spaced from the sides thereof and a longitudinal midship partition extending from the bottom of the shell or keel to the top or deck of the expansion trunk, said expansion trunk communicating with main tank spaces below the second deck and at opposite sides of the ship.

2. A tank ship comprising a shell, a main deck, a second deck, an expansion trunk extending from the second deck up through and to a point above the main deck and having walls extending longitudinally of the vessel and spaced from the sides thereof and a

longitudinal midship partition extending from the bottom of the shell or keel to the top or deck of the expansion trunk, said expansion trunk communicating with main tank spaces below the second deck and at opposite sides of the ship and summer tanks at opposite sides of the expansion trunk and between the main and second decks.

In witness whereof I affix my signature.

REGINALD PAULSEN.
